UNITED STATES PATENT OFFICE

LOUIS J. LOEFFLER, OF STAPLETON, NEW YORK

ANNUNCIATOR SIGNAL

Application filed January 5, 1931. Serial No. 506,672.

This invention relates to that type of annunciator in which a signal is communicated to a person at a distance by means of a visual disk which is oscillated to a predetermined 5 position to attract the person's attention, and reset to its normal position by means of a reverse movement of the disk.

The invention is designed to provide means for rotating the disk in an arc of a circle to 10 its initial or set position and retrograding it by means of an independent circuit.

An object of the invention is to provide a 15 pair of electromagnets, one being energized to set the disk initially and maintain it in that position until the current is applied to 20 reset or reverse the disk. In a device of this kind the self-contained electric reset signal requires but one-fifth of a rotation of the disk to reset or reverse it to its normal position, thereby requiring a very low current consumption due to its short oscillation.

One of the novel features contained in this 25 signal is that it does not rely on gravity to keep it in its respective position, but is accomplished by means of a spiral spring the stem or point of which rocks on the axis of the shaft controlling the visual, and once pulled over by the electromagnet is kept in that position at either set or reset.

The novel features of the invention are 30 more fully described in the following specification and claims, reference being made to the accompanying drawing in which:

Figure 1 represents a horizontal, longitudinal, section taken along the line 2—2 of Figure 3 of a device embodying this invention.

Figure 2 is a vertical, longitudinal, section taken along the line 1—1 of Figure 3.

Figure 3 is a front elevation of the same.

Figure 4 is a transverse section taken along the line 4—4 of Figure 1.

Figure 5 is a similar view showing the parts in a different position.

In the drawing the numeral 8 designates 45 a panel having a name plate 9 fastened to it, and a sight opening 11 covered with a glass disk 12 inserted in the opening. The panel has a tubular casing 14 fixed adjacent the 50 opening in the rear of the glass disk. The

casing is suitable for housing a single annunciator unit which is inserted into the casing from the rear, and by removing the screws 15, it can be easily removed. There can be any number of independent units mounted on 55 the panel, although the description of one will suffice for the other.

In the casing is enclosed an iron frame 16 having a front portion 17 with a series of sight openings and a bifurcated rear portion 18 constituting a pair of electromagnetic pole members. An electric bobbin 19 is wound on 60 each of the pole members and leads 20 connected to a source of electric energy control the energizing of the bobbins. The circuit is 65 completed by the return wire 21 connected to the frame.

To the bottom of the pole members is secured by means of screws 22 a disk 23 of insulating material having centrally mounted 70 thereon a rotor shaft 24 with an indicator comprising a visual disk 25 fixed to its upper end. The disk has white coloring to denote when it is in register with the openings and black coloring intermediate to show when the 75 disk is moved to the sight openings. The rotor shaft is equipped with an armature 26 having upturned ends and studs 27 forming stops to prevent excessive movement of the armature. The armature has a notched insulating washer 28, and a spiral spring 29 with 80 one end secured to an arm or support 30, and the other end wiping in the notch coacts to position the armature.

The position of the spiral spring is shown 85 in Figure 4 after the visual has been reset, and in Figure 5 it shows the position of the spring with the visual set. The notched washer allows the spring to rock or move 90 from right to left, the free action, however, is held in check as to its lateral movement. The spring acts as a check to compensate for the sudden pull of the magnet on the armature transmitting uniform oscillation to the visual disk and preventing rebound after 95 the end of its stroke.

The armature, as shown in Figures 4 and 5, is in the form of two arms extending from the axis of the rotor and by energizing the left hand magnet the armature is pulled in 100

the direction of the arrow as indicated in Figure 4 setting the visual disk, but when it is desired to reset or reverse the disk the opposite arm is attracted by energizing the right hand magnet, thus pulling the arm in the direction of the arrow shown in Figure 5.

What I claim is:—

An annunciator signal comprising an open ended cylinder, a unitary element adapted to 10 be inserted at one open end of and contained within the cylinder and comprising a member at one open end of the cylinder and a pair of arms extending rearwardly of and perpendicularly to said member, the free ends of 15 said arms being turned inwardly and then back upon said arms and spaced therefrom, an insulating disc mounted at the bends in said arms, a coil mounted on the free end of each of said arms, a rotor shaft having one 20 end journaled in the center of said member extending rearwardly between said coils and having its other end journaled in said insulating disc, an armature comprising a pair of oppositely disposed arms mounted on said 25 rotor shaft, each of said arms lying adjacent one of said coils, and a second member fixed to said rotor shaft adjacent said first mentioned member, said members including means whereby a signal is given when the 30 second member's position is changed with relation to the first mentioned member.

In testimony whereof I have hereunto set my hand.

LOUIS J. LOEFFLER.
